CLAIM

The ornamental design for an outdoor furniture cover, as shown and described.

DESCRIPTION

FIG. 1 is a perspective view of an outdoor furniture cover showing my new design;

FIG. 2 is a front elevational view of the outdoor furniture cover;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The cross-hatching shading in the Figures is fragmentarily shown for convenience of illustration, it being understood that the cross-hatching is uniformly continued over the surface on which it appears.

(Continued)

The broken lines shown in the drawings are to show environment and form no part of the claimed design.
